(57) **CLAIM**

The ornamental design for a gas burner, as shown and described.

DESCRIPTION

FIG. 1—an exploded perspective view of the gas burner of the present application, pointing out its cover and its base;
FIG. 2—a side view of the burner in the condition of cover mounted to the base;

FIG. 3—a second side view of the gas burner of the present application in the condition of cover mounted to the base, pointing out an inlet of the gas-injecting nozzle, as shown in FIG. 1; and,

FIG. 4—a top view of the gas burner of the present application, as shown in FIG. 2.
